NON-REUSABLE RECEPTACLE

Cedric C. Sopia, Forest Lake, Minn., and Henry Papp, Santa Clara, Calif., assignors, by mesne assignments, to General Mills, Inc., Minneapolis, Minn., a corporation of Delaware

Filed Feb. 24, 1959, Ser. No. 795,273
7 Claims. (Cl. 222—193)

This invention relates to non-reusable receptacles. More particularly, it relates to an inexpensive non-reusable receptacle uniquely constructed to facilitate its connection in fluid communicating relation with a conduit or other receptacle.

There are many instances where it is desirable that a receptacle for a given product be manufactured in such a manner that it is non-reusable. One example is a receptacle for a mixture of flock and adhesive, the latter being in dry powder form, wherein it is important that the receptacle be airtight. Unscrupulous individuals have been known to attempt to reuse such receptacles by imperfectly resealing them with the result that the bags leak and cause considerable damage and messiness. Such inferior products are incapable of detection without costly inspection methods and therefore it is highly desirable that the bag be so constructed that when it is opened, it will be impossible for such an individual to reseal the bag without greater expense being involved than would be involved in the original cost of the container or receptacle. It is also important therefore that the construction of the receptacle itself be of such low cost that such attempts to imperfectly reseal the receptacle will be discouraged. Our invention is designed to satisfy all of these desirable conditions and to at the same time provide highly improved means for connecting the receptacle to a flock gun, for example, or to another receptacle or other type of conduit. From the description given below, it will be seen that we have designed a unique receptacle and also a flock gun of unique construction which when utilized together yield a highly improved performance.

It is a general object of our invention to provide a novel and improved receptacle of simple and inexpensive construction and improved efficiency.

A more specific object is to provide a novel and improved receptacle capable of being manufactured inexpensively and incapable of being reused without the cost thereof amounting to more than the original cost of the container.

Another object is to provide a novel and improved receptacle which when opened will be capable of being readily attached in a simple manner to a conduit, gun, or other receptacle.

Another object is to provide a novel and improved receptacle which when opened will provide an unobstructed opening consisting of a section of the wall of the receptacle being removed.

Another object is to provide a novel and improved receptacle having unusually simple and novel means for opening the same quickly and effectively.

Another object is to provide a novel flock gun construction having inherent attachment means adapted to cooperatively engage inherent wall structure of a novel receptacle to connect the two in fluid communication in a highly and improved effective manner.

2

These and other objects and advantages of our invention will more fully appear from the following description, made in connection with the accompanying drawings wherein like reference characters refer to the same or similar parts throughout the several views and in which:

FIG. 1 is a side elevational view of one embodiment of our invention with portions thereof broken away;

FIG. 2 is a rear elevational view of the receptacle which we have designed to hold the flock and facilitate attachment.

FIG. 3 is a plan view of our flock applying gun;
FIG. 4 is a side elevational view of the gun.

FIG. 4 is a side elevational view of the gun with the flock containing receptacle removed therefrom;

FIG. 5 is a sectional view taken along lines 5—5 of FIG. 3;

FIG. 7 is a rear elevational view of the sealing and gun engaging means carried by the flock containing receptacle; and

FIG. 8 is a sectional view on an enlarged scale taken along lines 8-8 of FIG. 2.

This application is related to our co-pending application entitled Method and Apparatus for Applying Flock, Serial No. 785,945, filed January 9, 1959, now Patent No. 3,021,079. The invention claimed herein consists of the unique bag construction and the combination thereof with the unique gun construction. In our co-pending application, we are claiming the method and the specific features of the flock applying gun.

The embodiment of our invention that is shown in FIGS. 1-8 includes, a receptacle indicated generally by the numeral 10 which is secured to a flock applicator gun indicated generally by the numeral 11 which in turn is connected to a container 12. The invention disclosed with respect to the receptacle 10 alone and in combination with the applicator gun is claimed herein.

The receptacle 10 is preferably a bag having wall structure formed of thin flexible heat sealable material 13 such as polyethylene. The particular receptacle 10 which we utilize with our flock applicator gun 11 is provided with an annular thickened resilient portion 14 which is in the nature of an outwardly extending annular rib. This rib 14 may be formed, if desired, in the construction of the bag or, as preferred and as shown herein may be applied to the receptacle 10 by heat sealing such a structure as the thickened portion 14 to the wall structure of the bag. This can best be seen by reference to FIGS. 7 and 45 8. A second relatively thick portion which is annular in shape and preferably concentric with the annular rib 14 is designated by the numeral 15 and this thickened portion 15 is likewise heat sealed to the wall structure 13 of the bag. It will be noted by reference to FIG. 8 that there 50 is a relatively thin intermediate portion 16 also heat sealed to the wall structure 13 of the bag and disposed between the thickened annular portion 15 and the thickened annular portion 14. This relatively thin area serves a very useful purpose as will be hereinafter described. It will 55 also be noted that a tab 17 is carried by the thickened portion 15. The purpose of this unique construction is to provide a ready means for opening the receptacle 10 in such a manner that it will not be reusable and will provide a quickly available opening within the annular rib 14, for when the user pulls on the tab 17 the thickened 60 portion 15 will be torn from the wall structure 13.

annular portion 15 will tear the relatively thin area 16 to thereby remove all of the wall structure of the bag within the thickened annular portion 14. This provides the necessary opening for communication between the interior of the receptacle 10 and the interior of the material-conveying branch conduit of the gun 11 which will be hereinafter described.

We have found that we can obviate the disadvantage of clogging of the orifices through which the adhesive actuator is sprayed by mixing the flock well with a powdered adhesive within the receptacle 10 so that each particle of the flock will carry at least one particle of adhesive and preferably will be dusted on all sides with such adhesive. Thus, when the flock becomes airborne and is carried outwardly from the receptacle 10, it carries with it a certain amount of powdered adhesive which can be actuated by water or some other satisfactory liquid.

The container 12 may be an ordinary type container, preferably with a threaded upper end portion adapted to threadedly engage a cover member indicated generally by the numeral 18. This cover member 18 of the gun 11 carries an air conduit 19 which is adapted to be connected to a source of a strong flow of air. For the sake of simplicity and to make my apparatus more readily usable by housewives, we have found that the air conduit 19 may be connected by a flexible hose such as 20 to the discharge of a vacuum cleaner of a type which is commonly found in modern homes. The vacuum cleaner and the connection thereto has not been shown herein because it does not constitute a part of the invention and because any readily available source of flow of air may be utilized.

The air conduit 19 has a branch conduit 21 which as shown has a discharge end portion indicated by the numeral 22. A tube 23 extends within the branch conduit 22 and terminates at the discharge end portion as best shown in FIG. 5. This tube 23 extends downwardly through the wall structure of the branch conduit 22 and through the cover 18 to a position adjacent the bottom of the container 12 as best shown in FIG. 1. The tube 23 is positioned in this manner so that as the strong flow of air rushes through the air conduit 19 and the branch conduit 22, the water or other adhesive actuator which will be carried in the container 12 will be drawn outwardly through the small tube 23 and discharged at the discharge end portion 22 whereat it will be broken into fine spray form by the action of the outwardly rushing air through the discharge end portion 22 of the branch conduit 21. It will be noted that the spray of water emanating from the tube 23 will be in an unconfined flow.

The air conduit 19 has a second branch which constitutes a material-conveying branch conduit 24. This branch conduit 24 extends parallel to the branch conduit 21 for a major portion of its length and then angles inwardly and terminates in a terminal portion indicated by the numeral 25. It will be noted that this terminal portion 25 is directed in such a way that the flow therefrom will converge with the flow from the discharge end portion 22 of the branch conduit 21 and that the flow from each of these branch conduits will be unconfined at their point of juncture.

The material-conveying branch conduit 24 has a transversely extending barrier or plug 26 within which is a relatively small opening 27 which extends longitudinally of the branch conduit 24 and gives direction to the flow of the fibrous material such as flock and adhesive after it leaves the receptacle 10. The major portion of the air which flows into the branch conduit 24, however, is directed laterally by a flow directing element such as scoop 28. This scoop 28 as can best be seen in FIGS. 1 and 3 extends laterally to within the confines of the receptacle 10 and has its opening directed downwardly and slightly rearwardly so as to cause the flow of air to be directed toward the bottom of the receptacle 10 and thereby insure that the flock and adhesive will be properly entrained in the flow of air which is forced through the

receptacle. It will be noted that the scoop 28 is disposed rearwardly of the barrier 26. The material-conveying conduit 24 is also provided with a material inlet 29 and it will be noted that this inlet is disposed forwardly of the barrier 26. Thus, it can be readily seen that the major portion of the air flow which enters the material-conveying conduit 24 passes laterally into the receptacle 10 via the scoop 28 and entrains a portion of the flock and adhesive which it carries outwardly with it through the material inlet 29 back into the interior of the material-conveying conduit 24. As it re-enters the material-conveying conduit 24, the flow is given a directional impetus by the minor portion of the air flow which passes longitudinally of the material-conveying conduit 24 through the opening 27 and thus the airborne flow of flock and adhesive is carried outwardly longitudinally of the discharge end portion 25 of the branch conduit 24. It will be noted that the flow of flock and adhesive is unconfined after it leaves the discharge end portion 25 and that it remains in this form until it converges with and intermixes with the flow from the branch conduit 21 at approximately the point indicated by the letter X in FIG. 3.

It will be noted that the material-conveying conduit 24 has a recessed portion 30 which is shaped to conform to the shape of the annular thickened portion 14 of the receptacle 10. The size of this recessed portion is such that the resilient rib 14 will fit therein in snug frictional engaging relation. It will also be noted that the material carrying branch conduit 24 also supports a pair of upwardly sharpened pins 31 and 32 at the upper side of the recessed portion 30. These pins 31 and 32 are provided to cooperate with apertures 33 and 34 in a tab portion 35 connected to the rib 14. To apply the receptacle 10 to the gun 11 the user merely pulls the tab 35 17 and thereby opens the receptacle 10 as hereinbefore described and then inserts the pins 31 and 32 in the openings 33 and 34 and perforates the sealed off portion of the bag and then snaps the annular rib or thickened portion 14 into place within the recessed portion 30 of the branch conduit 24. This provides an extremely simple, effective and quick means for positively securing the receptacle 10 in sealed relation to the gun 11.

Each of the branch conduits 21 and 24 is provided with a slidably valve which interlocks so that the user may always rest assured that the branch conduit 21 has air flowing therethrough whenever air is flowing through the branch conduit 24. The branch conduit 24 is provided with a vertically slidably imperforate valve member 36 which has a laterally extending ear 37 that extends toward the branch conduit 21. Directly opposite to this valve member 36 and extending across the interior of the branch conduit 21 is a second valve member 38 provided with a laterally extending interengaging ear 39 which as best shown in FIG. 1 overlaps the ear 37 so that whenever the valve 36 is lifted to open the same, the valve 38 must also necessarily be lifted and opened therewith. The valve 38 is provided with a by-pass 40 which causes the flow of air to be directed outwardly of the gun through the upper portion of the valve 38 when the valve is closed.

It will be noted that in the receptacle construction disclosed herein the resilient annular rib 14 and the second annular thickened portion 15 as well as the intermediate portion 16 therebetween has been described as heat sealed to the wall structure of the bag. It will be readily understood, of course, that the wall structure of the bag could be formed initially with the rib 14, intermediate portion 16 and thickened portion 15 incorporated in the bag as initially constructed. We have shown these elements in the instant application as being applied to the original wall structure of the bag by heat sealing the same thereto as well as the material extending between the boundaries of the thickened portion 15. It will be readily appreciated however, that for all practical purposes, the material which has been heat sealed to the initial wall

structure of the bag constitutes (for all practical purposes) an integrally formed construction and we have so considered it herein.

From the above it can be seen that we have provided a unique bag construction which has several definite advantages. It will be noted that as a result of the area within the rib 14 being torn completely away, it is impossible for anyone to reuse the bag without becoming involved in considerable expense which in all probability will exceed the total construction cost of the bag initially. It will also be noted that the opening of the bag can be accomplished in an extremely simple manner by merely pulling upon the tab 17, which action will cause the intermediate portion 16 to tear so that the entire wall structure within the annular member 14 will be removed. Thus a clean and sufficiently large opening is provided for ready passage of the flock and adhesive therethrough.

It will also be noted that the resilient annular rib 14 cooperates with the recessed portion 30 of the air conveying conduit 24 to effectively connect the interior of the receptacle 10 with the interior of the material-conveying conduit. The effectiveness of this seal can be most readily appreciated when it is realized that a strong flow of air is forced through the gun and through the receptacle without any leaking taking place between the recessed portion 30 and the rib 14. The tab portion 35 which is pierced by the sharpened pins 31 and 32 of the gun preclude the bag being knocked free of the gun in the event an obstacle is struck with the bag while moving the gun and bag together. In other words, the securing action provided by the pins 31 and 32 and the tab portion 35 constitute a precautionary locking means to prevent the seal between the rib 14 and recessed portion 30 being broken as the result of an accident.

It should also be noted that a non-reusable bag is important in the manufacture and distribution of products such as flock and powdered adhesive. Unscrupulous individuals might attempt to reuse these bags in such a manner that small air leaks would not be discernible to the average purchaser, with the result that the material within the receptacle would take on moisture and cake and thereby, of course, become completely valueless and incapable of use.

An additional advantage of our unique receptacle is that it can be manufactured so inexpensively. Receptacles such as are disclosed herein can be manufactured very simply and inexpensively through the usual procedure of taking a conventional polyethylene bag and heat sealing to one wall structure thereof, a tab of similar material having the rib 14, the thickened portion 16 and the intermediate portion 15 therebetween formed thereon. When such a tab is heat sealed as shown in the drawings, the resulting receptacle is ready for use and can be manufactured and distributed in large quantities at relatively low cost.

Another advantage of this type of non-reusable receptacle is that its use so readily facilitates the manufacture and sale of a product such as a mixture of flock and adhesive. It is a simple matter for the user to disconnect the emptied receptacle and substitute another filled receptacle therefor with a consequent substantial saving in time, effort and inconvenience. In this connection, it will be noted that it is not necessary for the user to handle the flock and adhesive at any time in an unsealed condition. This is important for the handling of such material normally has considerable messiness attendant therewith.

It will, of course, be understood that various changes may be made in the form, details, arrangement and proportion of the parts without departing from the scope of our invention.

What is claimed is:

1. A non-reusable receptacle comprising a closable bag having a polymeric wall structure with an outer surface, and an annular rib element having an inner edge

secured to the outer surface of the polymeric wall structure of said bag, said rib element being adapted to frictionally engage the walls of a recess in a conduit of a materials applicator, the polymeric wall structure of said bag within said rib element being continuous and readily tearable, means connected to the portion of said wall structure located within said rib element which when a force is applied thereto exerts a force normal to said portion at substantially where said inner edge is secured to said wall structure and thereby providing a shearing stress which acts along said edge to cause said wall structure within said rib element to tear along said inner edge.

5 2. The structure defined in claim 1 where the entire wall structure of said bag is formed of a readily tearable polymeric material.

15 3. The structure defined in claim 1 in which said connected means is a tab secured to said readily tearable polymeric wall portion to facilitate removal thereof from within said annular rib.

20 4. The structure defined in claim 1 in which, said bag wall structure has a second rib member which is thinner than said annular rib element, said second rib being disposed within said annular rib, having a shape corresponding to a portion of the inner edge of said annular rib, being in spaced relation thereto and being secured to said wall portion disposed within said annular rib to facilitate removal of the readily tearable wall portion within said annular rib.

25 5. The structure defined in claim 4 in which, said second rib member disposed within said annular rib element is connected thereto by a relatively thin narrow intermediate portion whereby said intermediate portion will tear when a pulling force is exerted on said second rib member to thereby remove all wall structure within said annular rib.

30 6. In a fibrous material applicator, a gun having a material-conveying conduit adapted to be connected to a source of rapid flow of air, said conduit having a recess formed in its wall structure and having means at one point in the conduit for introducing air into said recess and having means at another point farther along in said conduit for allowing air to pass from said recess into said conduit, and a bag having an annular outstanding rib element on its outer wall surface, the outer dimensions and shape of said rib element being the same as the size and shape of said gun recess, the wall structure of said bag within said annular rib element having an opening therein, said rib element extending into said recess to frictionally engage the inner surfaces of said recess and thereby frictionally securing said bag to said gun with the interior of said bag in fluid communication with the interior of said conduit via said recess.

35 7. In a fibrous material application, a gun having a material-conveying conduit adapted to be connected to a source of rapid flow of air, said conduit having a recess formed in its wall structure and having means at one point in the conduit for introducing air into said recess and having means at another point farther along in said conduit for allowing air to pass from said recess into said conduit, outwardly extending impalement means upwardly mounted on said gun adjacent said recess, a bag having an annular outstanding rib element on its outer wall surface, the outer dimensions and shape of said rib element being the same as the dimensions and shape of said recess, the wall structure of said bag within said annular rib element having an opening therein, and a tab element with apertures therein connected to said rib element, said rib element extending into said recess to frictionally engage the inner surfaces of said recesses and said tab element apertures being impaled on said impalement means, said frictional engagement and said aperture impalement cooperatively securing said bag to said gun with the interior of said bag in fluid communication with the interior of said conduit via said recess.
